COMBINED STONE SURFACING AND
SAWING MACHINEAnthus D. Oldham, Bedford, Ind., assignor to
Indiana Limestone Company, Bedford, Ind.

Application May 28, 1931. Serial No. 540,728

8 Claims. (Cl. 125—3)

The invention to which the following description relates comprises a machine by which may be accomplished the combined operations of dressing the surface of a slab of stone and simultaneously cutting the slab by means of a tandem multiple bladed rip saw, effective in both directions of travel of the machine.

It is an object of my invention to combine a maximum efficiency for surfacing with a high degree of speed of operation, adjusting the speeds of the several parts in proportion to their individual requirements.

It is a further object of my invention to design a machine capable of surfacing limestone and at the same time producing a plurality of cuts with a great simplicity of machine parts. The various elements of the machine are so designed as to be inexpensively replaced or adjusted or interchanged.

20 It is also an object of my invention to improve machines of this character to allow the tools to travel over the work in both directions of travel thereby minimizing lost motion and idle time.

25 Among the objects of my invention it will be evident that this machine can be controlled with the surfacing and sawing operations independent each from the other and separately adjusted to carry out each operation under the most favorable and efficient conditions if so desired. However, the primary object of the invention is to perform successive operations on the stone simultaneously.

As indicating my invention I have shown by way of example in the attached drawings the preferred form of the machine in which:

Fig. 1 is a side elevation;

Fig. 2 is an end elevation of the same, and

Fig. 3 is a top plan view of the machine.

40 Referring to the drawings in which like parts are indicated by the same numerals I have shown the machine to be constructed in the following manner. A foundation 1 of any desired length is provided of concrete construction and the center portion thereof rises as a table to support the horizontal bed 2 upon which the stone slab 3 is placed for treatment by the machine.

The foundation extends laterally to include I-beams 4 which in turn form the supports for rails 5, 5.

The surfacing and cutting machine itself is mounted upon bridge trucks 6, 6. These trucks include anti-friction bearings 7, 7 and wheels 8. 55 Side standards 9 rise above the bridge trucks and

the latter are separated by the panels 10, and 11 of the frame.

Vertically at each end of the frame is a series of guides 12 upon which are mounted saddles 13, 14 and 15 respectively. The saddles 13 and 14 form part of a sliding carrier 16 upon which is mounted the power means for the tandem saw.

This consists in an electric motor 17 mounted on the carrier 16 and connected by means of the flexible coupling 18 to the bearing spindle 19. The spindle 19 passes through a journal bearing 20 which accommodates one end of the gang saw spindle.

The saw consists of a spindle 21 carrying a plurality of circular saw blades 22, 22. These blades are fastened in adjustable positions along the length of the spindle 21 by means of the split collars 23, 23.

The opposite end of the spindle 21 is journalled in the journal bearing 24 which in turn forms part of a table 25 mounted on the saddle 15. The table 25 is adjustable axially of the saw spindle by means of the screw 26 which in turn is controlled by the hand wheel 27 and locked into position by the lock 28.

80 The saddles 13, 14 and 15 together with the gang saw may be raised and lowered by the simultaneous operation of the screws 29, 30 and 31. These screws rest upon thrust bearings 32, 32 on the frame.

85 Rotation of these screws 29, 30 and 31 is accomplished by means of worm wheels 33 engaging worms 34 on the shaft 35.

The shaft is connected by means of a beveled gear set 36 through a coupling 37 and a worm and gear set 38 to a flexible coupling 39. The flexible coupling 39 is driven in turn by the shaft of the electric motor 40.

90 Each end of the machine carries a multiple gang sawing equipment of the above description.

95 The surfacing wheel or grinder is mounted centrally of the machine and adapted for vertical adjustment between the parts of the frame. The surfacing wheel 41 is mounted on a spindle 42 which in turn is carried in the journal boxes 43 and 44. The journal box 44 forms part of a horizontal table 45. This table has four saddles 46, 46 which are vertically movable in slides 47, 47 on the frame. On the table 45 on the opposite side from the surfacing wheel there is mounted an electric motor 48 which is connected to the spindle 42 through the journal box 44 by means of a flexible coupling 49 so that the surfacing wheel may be driven as desired.

100 The opposite journal bearing 43 is mounted in 110

a carriage 50 which has opposed saddles 51, 51 for vertical adjustment. The journal box 43 is slidable in and out of the carriage 50 by means of screw shafts 52, 52. The shafts 52, 52 carry 5 gears 53 which are operated by a pinion 54. A hand wheel 55 carries a shaft 56 which in turn carries the pinion 54. In this way the journal box 43 may be adjusted and locked in position by means of the lock 57 operating on the shaft of 10 the hand wheel 55.

Similar elevating screws 58, 59, 60, 61, 62 and 15 63 are journaled in the frame to serve for raising and lowering the saddles upon which the surfacing wheel and driving motor are mounted.

This is accomplished by means of an electric 20 motor 64 mounted upon a part of the frame and connected to the worm gears 65 through a coupling 66. The gear 65 is connected to shafts 67, 68. Shaft 67 operates the elevating screw 58 by means of a worm and gear connection 69. Shaft 25 68 running in the opposite direction controls the elevating screws 59 and 60 by means of a similar worm and screw 69, 69.

Leading from the worm gear 65 is a coupling 20 which through shaft 71 and coupling 72 is connected to a second worm gear 73 similar to that shown at 65. The worm gear 73 is connected by means of shaft 74 and coupling 75 to a worm and gear 69 which in turn is connected with the 30 elevating screw 61.

From the worm gear 73 the shaft 76 extends in an opposite direction beyond coupling 77. The shaft 76 operates the elevating screws 62 and 63 through worms and gears 69, 69.

The travel on the rails 5 is accomplished by 35 means of the multiple-speed motor 78. The shaft of this motor operates through coupling 79 and the worm and gear 80 to drive the beveled gear set 81. From the latter through clutch 82 power 40 is delivered to a shaft 83 extending from side to side of the frame. At opposite ends of the shaft 83 are bevel gears 84. The bevel gear 84 delivers power through shaft 85 to bevel gear 86 mounted near the drive wheel 8. The driving 45 connection passes through shaft 87 and the worm gear 88. Rapid traverse of the machine is accomplished from motor 78 through the extension shaft 89 out of the worm gear 80. This extension carries a multiple belt sheave 90 the belts of 50 which 91 also pass around the sheave 92. This sheave is loose upon the shaft 83 but is connected in driving engagement to it by the clutch 82 when the latter is disengaged from the bevel gear 81 allowing the latter to run free. A suitable 55 clutch and speed control are provided for accomplishing this high speed travel.

As above described this combined device consists of a traveling carrier in which there is centrally disposed a surfacing wheel which may be either cylindrical or have such a contour as to give the stone slab the desired mould or finish. This surfacing wheel is vertically adjustable during operation and rotates at a speed under the control of the operator. As the carrier travels from end to end of the bed the surfacing wheel is followed by one of the multiple gang cutters. This cutter operates at the desired peripheral speed independent of the travel of the carrier or the operation of the surfacing wheel. The cutter may also be elevated or depressed as desired.

At the limit of travel the slab which has been surfaced and cut into strips is removed and replaced by another slab. The return movement of the carrier accomplishes the surfacing and cutting of this slab in the manner above described.

In this operation the cutter first used will be elevated and the one at the opposite or following end of the carrier brought into cutting position.

The device, is therefore adapted for flexible independent carrying out of the several operations.

It will be understood that numerous variations in minor details are included within the scope of the invention as defined in the following claims.

What I claim is:—

1. A stone working machine comprising a bed, a track, a truck on the track, longitudinally spaced standards on the truck, guides on the opposed sides of the standards, slides on the guides, a platform connecting certain of said slides, a shaft journaled on said platform, means for driving the shaft, a bearing mounted on certain of said slides, a rotary surfacing tool carried by the shaft and said bearing, and power operated means for adjusting the platform and bearing simultaneously.

2. A stone working machine comprising a bed, a track, a truck on the track, longitudinally spaced standards on the truck, guides on the opposed sides of the standards, slides on the guides, a platform connecting certain of said slides, a shaft journaled on said platform, means for driving the shaft, a bearing mounted on certain of said slides, a rotary surfacing tool carried by the shaft and said bearing, a feed-screw on each guide and a common operating means for said feed-screws.

3. A stone working machine comprising a bed, a track, a truck on the track, longitudinally spaced standards on the truck, guides on the opposed sides of the standards, slides on the guides, means for simultaneously adjusting the slides on the guides, a rotary surfacing tool carried on said slides, actuating means for said tool, a second series of guides on the outer ends of the standards, slides on said second series of guides, means for simultaneously adjusting said slides, a rotary cutter carried by said slides and power actuating means for said cutter.

4. A stone working machine comprising a bed, a track, a truck on the track, longitudinally spaced standards on the truck, guides on the opposed sides of the standards, slides on the guides, means for simultaneously adjusting the slides on the guides, a rotary surfacing tool carried on said slides, actuating means for said tool, a second series of guides on the outer ends of the standards, slides on said second series of guides, feed-screws for the slides on said last named guides, means for simultaneously operating said feed-screws, a second stone-working tool carried by said slides and power actuating means for said last named tool.

5. A stone working machine comprising a bed, a track, a truck on the track, longitudinally spaced standards on the truck, guides on the opposed sides of the standards, slides on the guides, a rotary surfacing tool carried on the slides, actuating means for the tool, guides on the opposite outer ends of the standards, slides on said guides, a rotary tool carried on the said slides at each outer end of the standards, power actuating means for said last named tool, and means for adjusting each said tool into position for operation following the operation of the surfacing tool.

6. In a stone-working machine, a stationary work-support, of indeterminate length, a pair of rails on one side of said support, a single rail on the opposite side of said support, a carrier mounted on said pair of rails, a supplementary truck

mounted on the single rail, said carrier having an extension over the support and sustained by the supplementary truck, two longitudinally spaced series of standards on the carrier and truck, and a stone-working tool transverse of the carrier and supported on opposite sides of the work by one of said series of standards.

7. In a stone-working machine, a stationary work-support of indeterminate length, a pair of rails on one side of said support, a single rail on the opposite side of said support, a carrier mounted on said pair of rails, a supplementary truck mounted on the single rail, said carrier having an extension over the support and sustained by the supplementary truck, standards on the carrier and supplementary truck, a stone-working tool mounted on said standards trans-

versely of the work and means on the carrier for actuating the tool.

8. In a stone-working machine, a stationary work-support of indeterminate length, a pair of rails on one side of said support, a single rail on the opposite side of said support, a carrier mounted on said pair of rails, a supplementary truck mounted on the single rail, said carrier having an extension over the support and sustained by the supplementary truck, standards on the carrier and supplementary truck, a stone-working tool mounted on said standards transversely of the work and power means on the carrier for moving the carrier and supplementary truck as a unit.
